UNITED STATES PATENT OFFICE.

JOHN F. ELLIOTT, OF CINCINNATI, OHIO, ASSIGNOR TO THE SINGER MANUFACTURING COMPANY OF NEW JERSEY.

PRESSER-FOOT FOR TWO-NEEDLE SEWING-MACHINES.

SPECIFICATION forming part of Letters Patent No. 427,561, dated May 13, 1890.

Application filed December 20, 1889. Serial No. 334,349. (No model.)

To all whom it may concern:

Be it known that I, JOHN F. ELLIOTT, a citizen of the United States, residing at Cincinnati, in the county of Hamilton and State of Ohio, have invented certain new and useful Improvements in Sewing-Machine Pressers, of which the following is a specification, reference being had therein to the accompanying drawings.

10 My invention has for its object to provide a sewing-machine having a roller-presser with an auxiliary presser which is vertically movable independently of the main or roller presser, and which serves as a guard and guide 15 for two closely-placed needles and as a stripper to prevent the work from being lifted, as this would cause a failure of a proper formation of loops of needle-thread for the point of the shuttle or looper to enter. My independent 20 presser is preferably carried by a sleeve surrounding the main presser-bar, and is yieldingly held down by a spring surrounding said bar and arranged between the said sleeve and the lifting-bracket.

25 In the drawings, Figure 1 shows a portion of a "Singer" sewing-machine with my invention applied thereto, the cap or face-plate of said machine being removed. Fig. 2 is a front end view of the same with the main or 30 roller presser and most of its carrying-bracket removed. Fig. 3 is a partial section on line 3 3, Fig. 2. Fig. 4 is a detail section of the auxiliary and main pressers, and Fig. 5 is a detail perspective view of the auxiliary 35 presser.

A denotes the sewing-machine head, and B the needle-bar, provided with two needles b, arranged diagonally to the line of feed, so as to form two closely-adjacent rows of stitches, 40 as is often desired in stitching the vamps of shoes and other work.

C is the main presser-bar, to the lower end of which is attached a well-known form of bracket C', which carries the roller-presser c, 45 which is the form of presser preferably used for leather-work, as it does not mar or scratch the surface thereof. Surrounding the lower part of the presser-bar C, and fitting closely in a proper aperture in the lower bearing-lug a 50 of the head A, is a sleeve or tubular bar D, to the lower part of which is attached, by a screw

d, the auxiliary presser and needle guard and guide d', the foot portion of which is, in the present instance, provided with two diagonally-arranged holes or eyes d² for the passage 55 of the two diagonally-arranged needles b. The auxiliary presser d' is held down by an independent coil-spring d³, surrounding the presser-bar C, between the lifting-bracket c' and the top of said sleeve, said spring thus 60 providing for vertical movements of the auxiliary presser independently of the main or roller presser, the latter being held down by the usual coil-spring c² above the lifting-bracket. The foot portion of the presser d' 65 is arranged in close proximity to the main or roller presser, and is preferably cut away slightly on one side, so that it may partially overlap the flange c³ of the said roller-presser; but the main portion of the bottom of said 70 foot will still be flush with the bottom of said roller-presser. The overlapping part of the said foot is, however, slightly above the said flange c³, so as not to interfere with the free 75 rotation of said roller-presser.

As hereinbefore stated, a roller-presser is the form of presser preferably used in sewing finely-finished leather, as it does not scratch or mar the surface thereof when pressing thereon above the feed-dog; but owing to 80 the fact that the pressing-surface of a roller-presser is continually changing it necessarily presses on the work outside of the needle or needles, and cannot be made to surround the latter as an ordinary foot-presser does. Thus 85 in sewing leather the work will not always be properly stripped from the needles as the latter rise, and if the work rises slightly with the needles loops for the shuttle to catch will not 90 result, this trouble being greater when two diagonally-arranged needles to form parallel rows of stitches are employed, one of said needles being farther from the roller-presser than the other; but by the employment of my auxiliary foot-presser, which does not necessarily 95 form a resistance-pressure for the feed, (for the reason that the pressure of the roller-presser is sufficient for that purpose,) and which therefore does not bear on the work 100 hard enough to scratch or mar the surface of the leather, this difficulty is avoided, my

auxiliary presser being constructed and arranged to bear constantly on the work when in operation beside and closely adjacent to the main presser, or, in other words, not being merely a needle-guard moving vertically with the needles, although serving in a measure to guard the needles when they are about to enter the work. The auxiliary presser is lifted with the main presser by reason of the engagement of some part of the latter with the former. This engagement is provided for in the present instance by arranging the shank or attaching part c^4 of the roller-carrying bracket C' immediately beneath the lower end of the sleeve D of the auxiliary presser d' and the shank of the said presser, so that when the main presser is raised from the work by the lifter E the auxiliary presser will also be raised; but as these parts of the auxiliary presser are above the parts of the main presser, by which they are engaged to be lifted, it results that the said auxiliary presser is free to have a vertical movement independently of the main presser.

The main and auxiliary pressers are arranged side by side and both bear on the work closely adjacent to the needles. The feed-points are beneath the main or roller presser, as denoted by the dotted lines in Fig. 1, but do not extend beneath the auxiliary presser. Thus if the auxiliary presser, which is rigidly attached to its bar, were not movable vertically independently of the main presser, a thicker portion of the work coming beneath the former would raise the latter, so that the feed would fail to act, and thus imperfect sewing would result; but owing to its independent spring my improved auxiliary presser will permit of the passage beneath it of portions of work thicker than are passing beneath the main or roller presser without disturbing the action of the feed. It thus results from my invention that in sewing with two needles, one of which is farther from the main presser than the other, the work is properly held down or "stripped" from the needles as the latter rise, so that their loops are properly thrown out, while the two closely-adjacent and slightly-

tapering needle-holes in the auxiliary presser-foot adapt the latter to serve as a guide and 50 guard for the needles to cause them to maintain their proper positions and prevent them from fouling or interfering with each other.

I am aware that it is not new to provide a sewing-machine with main and auxiliary 55 pressers; but I believe that I am the first to provide such a machine with an auxiliary presser which bears constantly on the work when in operation beside and closely adjacent to a main or roller presser, which is movable 60 vertically independently of the main presser, and which is also adapted to be lifted by the latter.

Having thus described my invention, I claim and desire to secure by Letters Patent— 65

1. In a sewing-machine, the combination, with a needle-bar carrying two closely-adjacent needles, of a main presser-bar C and roller-presser c , a tubular bar or sleeve surrounding said bar C , the auxiliary foot-presser d , 70 carried by the said tubular bar or sleeve and having the needle-guiding holes d^4 , said foot-presser bearing constantly on the work when in operation beside and closely adjacent to the said roller-presser c and around said needles, and independent springs for depressing the said roller and auxiliary pressers. 75

2. In a sewing-machine, the combination, with a needle-bar carrying two closely-adjacent needles, of a main roller-presser, an auxiliary foot-presser bearing on the work beside 80 and closely adjacent to the said main roller-presser and around said needles, and means for lifting said roller and foot pressers together. 85

3. The combination, with the roller-presser having the flange c^4 , of the auxiliary presser cut away slightly on one side and arranged adjacent to said roller-presser with its cut-away portion overlapping said flange. 90

In testimony whereof I affix my signature in presence of two witnesses.

JOHN F. ELLIOTT.
